Inventor:
William W. Kirchner

United States Patent Office.

WILLIAM M. KIRCHNER, OF PITTSBURG, PENNSYLVANIA.

Design No. 4,758, dated April 4, 1871.

DESIGN FOR A JELLY-GLASS.

The Schedule referred to in these Letters Patent and making part of the same.

To all whom it may concern:

Be it known that I, WILLIAM M. KIRCHNER, of Pittsburgh, in the county of Allegheny and State of Pennsylvania, have invented a new and improved Design for Jelly-Glass; and I do hereby declare the following to be a full, clear, and exact description thereof, reference being had to the accompanying drawings forming part of this specification, in which—

Figure 1 is a perspective view of a jelly-glass made after my improved design; and

Figure 2 is a like view of the same with the cap.

My design consists in a jelly-glass having a pentagonally-shaped mouth, and a pentagonally-shaped cap, with flanged edges to fit upon the mouth.

Around the mouth of the glass *a* is a bead, *b*, either continuous and unbroken or broken at intervals.

The cap *c* is of like shape, so as to fit on the mouth of the glass *a*.

The edges of three sides of the lid *c* are folded down and under, so as to fit around the bead, as at *c'*,

and the edges of the other two sides are bent down but little, so that it requires but a slight pressure to them over the bead, as at *c''*.

This cap slides onto the mouth of the glass, the three folded sides *c* fitting against the bead *b*, and the other two sides *c''* slipping or springing over it.

What I claim as my improved design, and desire to secure by Letters Patent, is—

1. A design for a jelly-glass having a pentagonally-shaped mouth, as described and shown.

2. A design for a pentagonally-shaped cap for a pentagonally-shaped jelly-glass, as described and shown.

In testimony whereof I, the said WILLIAM M. KIRCHNER, have hereunto set my hand.

WM. M. KIRCHNER.
